Patented July 20, 1976

240,629

DENTAL ARM REST CABINET

Raymond Cope, 4285 3rd Ave. S. (or P.O. Box 31053),
Birmingham, Ala. 35222

Filed Jan. 29, 1975, Ser. No. 545,178

Term of patent 14 years

Int. Cl. D24—02

U.S. Cl. D24—1 B

Fig. 1

Fig. 2

FIG. 1 is a top front perspective of a dental arm rest cabinet showing my new design; and

FIG. 2 is a bottom rear perspective thereof.

I claim:

The ornamental design for a dental arm rest cabinet, substantially as shown and described.
